SYNCHRONIZED RADIO TRANSMISSION

Wilmer L. Barrow, Newton, Mass., assignor to
 Sperry Gyroscope Company, Inc., Brooklyn,
 N. Y., a corporation of New York

Application August 5, 1941, Serial No. 405,466

16 Claims. (Cl. 250—1.64)

1

This invention relates to radio transmission systems and it refers more particularly to circuit arrangements for synchronizing the frequencies of currents at the transmitting and receiving ends of a transmission circuit. As a distinctive term, I have applied the name "synchrodyne" to the class of circuits disclosed herein for accomplishing this result.

"Synchrodyne" circuits are particularly adapted to provide stable reception for micro-wave signals and find great usefulness in obstacle detection and distance measuring systems in which micro-waves are reflected to the receiver from a remote object, for example, an aerial target. In the past, micro-wave receivers used in connection with such systems have been of the types commonly known as straight detector, tuned radio frequency amplifier and superheterodyne receivers. Difficulty has been experienced in securing stable reception with receivers of any of these types since the transmitting frequency in general is not absolutely steady nor is the transmitted wave purely sinusoidal in character. At ultra-high frequencies the transmitter frequency is subject to variation from a number of causes such as change in supply voltage, thermal drift, vibration and other effects. To receive signals from a transmitter whose frequency is subject to drift, it has previously been necessary to employ a receiver having a band width much greater than the nominal frequency band of the received signals, in order to allow for drift. A disadvantage of a wide band receiver lies in the resulting unfavorable signal to noise ratio, since this ratio is generally lower as the band width becomes greater, and in the greater number of stages of vacuum tube amplification required, since the gain per stage decreases as the band width increases. When a superheterodyne receiver is used, even though the transmitter frequency is held constant, great difficulty is experienced in securing sufficient stability of the receiver local oscillator to make practical the use of a narrow band intermediate frequency amplifier. For micro-wave reception, this imposes severe conditions on the design and operation of a receiver of this type.

One object of the present invention is to provide a receiving system which permits the use of a very narrow receiving band width, i. e., a high degree of selectivity at the receiver, without at the same time imposing undue frequency stability restrictions on either the transmitter or receiver.

2

Another object is to obtain an improvement in the signal to noise ratio of a superheterodyne type receiver at ultra-high frequencies by permitting a narrow band width intermediate frequency amplifier to be used.

Another object is to provide an obstacle detection system making use of reflected radio waves of ultra-high frequency in which the tuning of the detection system is constantly and automatically maintained.

A further object is to supply a stabilizing frequency to the receiver of a radio transmission system over a path other than the normal transmission path for securing a favorable signal to noise ratio by permitting increased selectivity of the receiver.

In the drawings,

Fig. 1 represents schematically a system for practising my invention, which I term the basic "synchrodyne" circuit, wherein a radio transmitter is connected to a receiver by a path supplemental to the radio transmission path, which may change direction due to reflection, for supplying a stabilizing frequency to the receiver.

Fig. 2 illustrates schematically a modification of my basic circuit wherein the transmitter carrier is modulated by a pulse or series of repeated pulses.

Fig. 3 illustrates schematically a distance measuring system utilizing the principle of my invention, in which the phase difference of the transmitted and received waves is utilized to indicate distance to a reflecting object or surface.

Fig. 4 is a schematic representation of another modification, wherein modulation is accomplished at a low frequency and frequency multiplication is employed to secure a high transmitting frequency.

Fig. 5 represents schematically a further modification wherein a high frequency bridge circuit composed of transmission lines is utilized as a balanced or carrier suppression modulator.

Referring to Fig. 1, there is illustrated a transmitting oscillator 10 for generating a carrier frequency f_0 , which may be in the ultra high frequency or micro-wave range, as is commonly the case in reflection systems for obstacle or target detection or for distance measurement. An adjustable directional radiator 11 of any suitable type, as for example that described by L. J. Chu and W. L. Barrow in a paper entitled "Electromagnetic horn design," published in "Electrical Engineering," vol. 58, pp. 333 to 338, is connected to oscillator 10.

The wave radiated from antenna or horn 11

at frequency f_0 , is illustrated as being directed toward an obstacle or target such as airplane 12 and the radiation reflected therefrom as being received by a suitably oriented directional receiving antenna or horn 13 which supplies a signal to a receiver 14 operating on the superheterodyne principle, of which the high frequency converter or first demodulator (hereinafter referred to as "the converter") and the intermediate frequency amplifier and second demodulator are indicated by blocks 15 and 16 respectively. It is to be understood that the intermediate frequency amplifier includes an intermediate frequency filter limiting the frequency band passed, as is common in receivers of this type. The output of the second demodulator (hereinafter referred to as "the demodulator"), is received by an indicator 17 which may be a meter or recorder of suitable type for exhibiting the receiver output.

At the transmitter, a source of modulation frequency such as modulation oscillator 18 supplies a modulation frequency f_1 to modulator 19 which also receives frequency f_0 from transmitter oscillator 10. The output of modulator 19 includes a component at the frequency f_0 and in addition components representing the sum and difference of f_0 and f_1 which will be referred to as the upper and lower side frequencies, respectively. Frequency f_1 is normally too low to appear as a component of appreciable magnitude in the output of a modulator designed for high frequency operation. When the carrier is modulated by a band of frequencies instead of by a single frequency then in place of side frequencies there appear upper and lower side bands, as is well known in the art. The output of modulator 19 is received by band pass filter 20 which selects one or both of the side frequencies and the output of the filter is transmitted by a wire line or supplemental radio path to frequency converter 15 for heterodyning therein the reflected f_0 wave received by horn 13 in the manner that the output of the local oscillator is utilized in the usual type of superheterodyne receiver.

In operation, assuming an unmodulated carrier f_0 to be employed, and if the transmitting antenna, or other radiator 11 is suitably oriented, for example, as the result of searching until a reflecting object is located, the radiated wave will strike obstacle 12 and a portion of the energy will be reflected to receiving antenna 13 and a signal will be applied at frequency f_0 to frequency converter 15. This converter also receives one of the side frequencies, for example, the upper side frequency f_0+f_1 , and as the converter is a modulator, that is a non-linear device, the difference of the carrier and side frequency will appear as one component in its output, this difference being the modulating frequency f_1 . It will be apparent that in the arrangement described the frequency stability of the signal passed to the intermediate frequency amplifier is independent of the frequency stability of the transmitting oscillator and depends only on the stability of the modulation oscillator. Since the latter oscillator operates at a relatively low frequency, its stability can be made high. By thus supplying a stable intermediate frequency signal, a narrow band filter can be used in the intermediate frequency amplifier with a resulting favorable signal to noise ratio, and also a relatively small number of stages in this amplifier.

While the heterodyning side frequency is supplied to converter 15 at all times, due to the directional characteristics of the transmitting and

receiving antenna no f_0 carrier is received unless the direction of transmission is altered by reflection and therefore an indication on meter 17 is obtained only when a reflecting obstacle is in the radiated field. If a variable amplitude signal is radiated by the transmitter, a received signal varying proportionally in amplitude but independent of frequency distortion due to drifting of the transmitter frequency may be obtained by transmitting a constant amplitude heterodyning side frequency to the frequency converter of the receiver.

Transmitting and receiving antennae 11 and 13 are shown in Fig. 1 as spaced from one another and directed substantially in opposite directions. In many arrangements, however, particularly when horn type radiators and receivers are employed the radiators may be separated by a relatively small distance and hence directed at substantially the same angle, particularly when transmitting to and receiving reflected radiation from an object at a considerable distance.

Referring now more particularly to the arrangement of Fig. 2, this is in general similar to that of Fig. 1 except that the signal supplied by transmitting oscillator 10 to transmitting antenna 11 is a modulated signal, the modulation here being shown as derived from pulse generator 21 connected to pulse modulator 22. The pulse method is peculiarly adapted for measuring distance to a reflecting object or surface and is well known in the art. It has been widely employed in one form to measure the height of the ionosphere and various modifications of this method have been proposed, or used, to measure the distance between an airplane and the earth, the transmitter being located in some cases on the plane and in some cases on the earth. Such systems of measurement require a high degree of frequency stability, which the "synchrodyne" circuit is well adapted to supply.

The operation of the system of Fig. 2 will be apparent from the described operation of that of Fig. 1. A series of recurrent pulses, which may each have a duration of the order of a few microseconds, is applied by generator 21 to pulse modulator 22 to produce corresponding pulses of the current at the frequency supplied by transmitting oscillator 10 and the modulated wave after reflection from reflecting surface 12, supplies the transmitted frequency f_0 to frequency converter 15 which also receives one or both side frequencies resulting from the modulation of f_0 by a sinusoidal frequency f_1 in modulator 19. Converter 15 passes to the intermediate frequency amplifier a pulse-modulated signal, which upon demodulation reproduces the original series of pulses as indications of indicator 17. As in the system of Fig. 1, the high degree of frequency stability secured permits a high signal to noise ratio to be attained by the use of a narrow band intermediate frequency filter, which is of great importance in pulse measurement systems, and the indication of the pulses is not distorted by frequency drift.

In Fig. 3 there is illustrated the application of the "synchrodyne" circuit to a system for measuring distance to a reflecting object by indicating the difference in phase of a transmitted and reflected wave. Distance to the object is proportional to the phase shift of the modulation envelope of the received wave relative to that of the transmitted wave, and this method has been suggested for the operation of radio altimeters and similar apparatus. In measuring arrangements of this type, stabilizing arrangements are

of great utility to eliminate spurious frequency drift, this providing greater sensitivity and increased range.

Transmitting antenna 11 and receiving antenna 13 are suitably oriented to radiate a wave toward reflecting object 23 and to receive the portion reflected therefrom. Carrier frequency f_0 supplied by transmitting oscillator 10, according to the arrangement of Fig. 3, is modulated in modulator 19 at a lower frequency f_2 supplied from an oscillator or other source 24. Current due to the modulated wave reflected from object 23 and received by antenna 13 is supplied, as in previously described arrangements, to a super-heterodyne type receiver, the converter, intermediate frequency amplifier and demodulator of which are represented by block 25. The heterodyning frequency for the converter is obtained, in principle, as heretofore described. In the arrangement of Fig. 3 the modulation of f_0 by f_1 , however, is shown as accomplished in balanced modulator 26, this being a type of modulator well known in the art which, by suitable connections, suppresses the carrier frequency and passes only the side frequencies, or side bands, thus doing away with the use of filter 20 of Figs. 1 and 2. Obviously, the combination of unbalanced modulator and filter, previously described, may alternatively be used in the arrangement of Fig. 3 or a balanced modulator may be employed for suppression of the carrier frequency f_0 in any other system described herein.

The output of the receiver demodulator includes a component at the frequency f_2 , and other components may be eliminated by well-known means. The demodulated frequency f_2 is applied to phase difference indicator 27, which also receives a signal at frequency f_2 from oscillator 24. Phase difference indicators are known in the art as for example, the type described by J. R. G. J. Blanchard et al. in U. S. Patent No. 1,968,068, issued July 31, 1934. If f_2 is chosen as the frequency of commercial power circuits, other well known instruments are available for indicating phase difference. It will be apparent that the phase difference indicated as that due to the distance traveled by the radiated wave before and after reflection from the reflecting object, and this difference, therefore, furnishes a measure of the distance of the object from the measuring apparatus.

Technical difficulties in the construction and operation of a carrier suppression modulator, or its equivalent, at ultra high radio frequencies, make it desirable in some cases to carry out the various modulating processes employed in connection with the arrangements described herein at frequencies lower than the radiated frequency. An arrangement for accomplishing this is shown in Fig. 4 in connection with an obstacle detection system in which transmitting oscillator 18 operates at a relatively low frequency in comparison with the radiated frequency which oscillator frequency is modulated in modulator 19 by the still lower frequency f_2 supplied by modulation oscillator 27. The frequency of the resulting modulated wave is then increased by frequency multiplier 28. Frequency multipliers are well known in the art, a type suitable for operation at high frequencies being described in U. S. Patent 2,086,904, issued to J. Evans, July 13, 1937. A similar process of frequency multiplication is employed in obtaining the side frequency for heterodyning purposes in receiver 25, this frequency

multiplication being accomplished by multiplier 29. In other respects the operation of the system of Fig. 4 will be apparent from the operation of the arrangements previously described.

Fig. 5 represents a modification of my invention in which modulation is accomplished by the use of a high frequency transmission line bridge circuit which includes a non-linear element at one of the bridge points. Bridge circuits employing transmission lines are described in my copending application Serial No. 376,253, filed January 23, 1941, Patent No. 2,416,790 granted March 4, 1947, and as there disclosed comprise four transmission lines having distributed electric constants, such as lines 30, 31, 32, 33 schematically represented in Fig. 5 of the present application, connected in tandem to form a closed bridge circuit. The construction of these lines may vary widely to include ordinary two wire lines, shielded conductor or coaxial lines, hollow pipe lines, dielectric guides, and other means for guiding electromagnetic waves known to those skilled in the art.

The four lines of Fig. 5 form two parallel transmission paths between transmitting oscillator 10 and a load (here illustrated as filter 34 in tandem with receiver 25) comprising lines 30, 31 and lines 32, 33, respectively. If these two transmission paths have similar characteristics an E. M. F. impressed across the junction of lines 30 and 32 will initiate the transmission of electromagnetic waves over the two paths which upon arrival at the filter 34 will have equal amplitudes and by suitable connections may be made to oppose and annul one another. Phase and amplitude adjuster 35 provides the means for adjusting the characteristics of the transmission path, 32, 33 to match that of the parallel path 30, 31. When suitable adjustments are made so that the two waves cancel one another direct transmission of energy from oscillator 10 to filter 34 at the frequency of the oscillator is prevented. Mixer circuit 35 at the junction of lines 30 and 31 is a non-linear device of any suitable type which receives an E. M. F. at frequency f_1 from modulation oscillator 18 for combination with the E. M. F. at frequency f_0 due to the arrival at the mixer of the wave travelling over line 30. The result of modulation in mixer 35 is a series of modulation products from which filter 34 may select, for example, the upper side frequency ($f_0 + f_1$) which is then applied to the frequency converter of receiver circuit 25 for heterodyning the frequency f_0 received by antenna 13 as in previously described circuits. By the use of transmission lines it is feasible to construct a bridge circuit which operates as a carrier suppression type modulator at extremely high frequencies and which retains its balance over a frequency range of considerable width.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim and desire to secure by Letters Patent is:

1. A system for measuring distance to a reflecting surface comprising a radio transmitter including a source of high frequency, means for generating recurrent pulses of short duration, a

modulator connected for modulating said high frequency by said pulses, a directional radiator connected to receive the output of said pulse modulator for selectively radiating a pulse modulated wave in the direction of the reflecting surface, a directional receiver receiving radiation reflected from said surface, said receiver being of the superheterodyne type, circuit means for supplying a heterodyning frequency derived from the transmitter frequency to the converter of said receiver, including a source of low frequency modulation, a modulator receiving alternating potentials at said high frequency and said modulating frequency, filter means for selecting from the output of said modulator at least one of the resulting side bands, circuit means for applying said side band to said frequency converter jointly with the received radio signal, said receiver including a demodulator for demodulating said converter output, and means for indicating said demodulator output.

2. A system for determining the position of an object capable of reflecting radio waves comprising a radio transmitter including an oscillator, a source of low frequency alternating potential, a modulator connected to said oscillator and source and a directional radiator for selectively radiating in the direction of the object, a directional superheterodyne receiver receiving radiation reflected from the object including receiving antenna means and a frequency converter connected thereto, circuit means for supplying to said converter the received radio frequency and a heterodyning frequency suitable to produce the intermediate frequency of said superheterodyne receiver including a modulation source, a modulator connected to said oscillator and to said modulation source and means for suppressing the oscillator frequency in the output of said modulator, and a phase difference indicator jointly actuated by a potential derived from the output of said converter and a potential from said low frequency source for indicating the phase difference of the common frequency of said two potentials.

3. An obstacle detection system comprising a transmitting oscillator, a modulation oscillator, a modulator connected to said two oscillators, a frequency multiplier connected to the output of said modulator, an adjustable directional antenna receiving the output of said multiplier for selective radiation in the direction of the obstacle, a second modulation oscillator, a balanced modulator connected to said oscillator and said second modulation oscillator, circuit means for selecting one of the side bands from the output of said modulator, a second frequency multiplier for multiplying the frequencies of said side bands, a directional receiving antenna receiving radiation reflected from the obstacle including a frequency converter connected to said second frequency multiplier and said receiving antenna, and means for exhibiting the output of said converter.

4. A radio transmission system comprising a transmitter having a transmitting oscillator, a frequency multiplier for increasing the frequency thereof and an antenna receiving the output of said multiplier, a receiver including an antenna receiving signals from said first antenna and a frequency converter, a source of modulation having a frequency lower than that of said oscillator, a modulator connected to said oscillator and said source, circuit means for suppressing the frequency of said oscillator in the output of said modulator, a second frequency multiplier for increasing the frequency of said modulator output,

75 circuit means for supplying the output of said multiplier to said frequency converter for altering the frequency of the received radio signals, and means for exhibiting the output of said converter.

5. An obstacle detection system including a transmitting oscillator, a directional antenna connected thereto for selectively radiating in the direction of the obstacle, a superheterodyne receiver receiving radiation reflected from the obstacle including a receiving directional antenna and a frequency converter connected thereto, carrier frequency suppression circuit means connecting said oscillator and said converter including a balanced bridge circuit, a source of modulation frequency equal to the intermediate frequency of said superheterodyne receiver connected to said bridge circuit at a point conjugate to said transmitting oscillator, said bridge circuit including a non-linear element combining signals received from said transmitting oscillator and said source for supplying a product of the modulation thereof to said converter.
- 10 6. An obstacle detection system as claimed in claim 3 in which said bridge circuit comprises transmission lines as arms thereof, the characteristics of said transmission lines being chosen to convey said transmitter oscillator frequency, substantially without loss.

- 15 7. An obstacle detection system as claimed in claim 3 in which said bridge circuit comprises transmission lines as arms thereof and in which phase and amplitude adjustments are provided for balancing said bridge circuit.
- 20 8. In a radio transmission system comprising a high frequency source of nominally constant frequency but subject to frequency drift and means supplied from said source for radiating a wave at the frequency thereof, a superheterodyne receiver of energy radiated by said means including a frequency converter, a source of modulation frequency harmonically related to the intermediate frequency of said receiver, a modulator, circuit means for supplying as inputs to said modulator a potential derived from said modulation source

- 25 and a potential derived from non-radiated energy supplied by said high frequency source, circuit means for applying as inputs to said converter the received wave and a sideband component of the output of said modulator to obtain as an output therefrom a signal insensitive to frequency drift of said high frequency source, and connected means actuated by said signal.
- 30 9. In a radio transmission system comprising a high frequency source of nominally constant frequency but subject to frequency drift, means connected to said source for radiating a wave at the frequency thereof and means for producing an amplitude modulation of the radiated wave, a superheterodyne receiver of energy radiated by said radiating means including a frequency converter, a source of modulation frequency equal to the intermediate frequency of said receiver, a modulator, circuit means for supplying as inputs to said modulator a potential derived from said modulation source and a potential derived from non-radiated energy supplied by said high frequency source, circuit means for applying as inputs to said converter the received wave and a sideband component of the output of said modulator to obtain as an output therefrom a signal reproducing amplitude variations of the radiated wave but insensitive to frequency drift of said high frequency source, and connected means actuated by said variable amplitude signal.

- 35 10. In a system for transmitting high frequency
- 40
- 45
- 50
- 55
- 60
- 65
- 70

quency energy to an obstacle and receiving a reflected portion thereof, a transmitter including a high frequency oscillator and a radiator supplied therefrom at a nominally constant carrier frequency subject to random drift, a superheterodyne receiver including a frequency converter, a source of modulation frequency equal to the intermediate frequency of said receiver, a modulator, circuit means for supplying as inputs to said modulator a potential derived from said modulation source and a potential derived from non-radiated energy supplied by said oscillator, means for selecting from the output of said modulator a sideband component, and circuit means for applying said selected component to said converter for reproducing said modulation frequency by combination with the received wave.

11. The method of obtaining a variable amplitude, constant first frequency signal corresponding to a variable amplitude signal radiated by a transmitter of varying carrier frequency comprising the steps of receiving the varying carrier frequency signal, modulating the varying transmitter carrier frequency at a substantially constant frequency intermediate to said first frequency and said carrier frequency, sending from the transmitter to the receiver a non-radiated signal of constant amplitude at one of the varying side frequencies resulting from said modulation and combining said received varying frequency signal with said varying side band signal to obtain said constant intermediate frequency signal varying in amplitude in correspondence with the radiated signal.

12. The method of receiving a substantially constant first frequency signal from a remote radio transmitter of slowly drifting carrier frequency, said signal having an amplitude substantially independent of said drift, comprising the steps of receiving a signal at the drifting transmitter carrier frequency over an unguided path, modulating the varying frequency at the transmitter at a substantially constant frequency intermediate to said carrier frequency and said first frequency, transmitting signals at one of the resulting side frequencies to the receiver over a guided transmission path and there combining the signals received by said two paths to obtain said constant intermediate frequency signal having an amplitude proportional to the amplitude of the radiated signal, and demodulating said intermediate frequency to obtain said first signal.

13. An obstacle detection system comprising a transmitting radio frequency oscillator, a directional radiator supplied thereby at substantially a single carrier frequency for selectively radiating a wave at said carrier frequency in the direction of the obstacle, a directional receiver of the superheterodyne type receiving radiation reflected from the obstacle and including a frequency converter, a source of modulating frequency equal to the intermediate frequency of said superheterodyne receiver, a modulator connected to receive potentials of substantially single frequency derived from said oscillator and said modulating source, circuit means for supplying said converter with a potential at one of the side frequencies resulting from modulation in said modulator jointly with a potential derived from the received

radiation, and means for exhibiting the magnitude of the component in the output of said converter having a frequency equal to the difference between that of said radio signal and said side frequency.

14. An obstacle detecting system comprising a radio transmitter having a high frequency source and a directional radiator connected thereto for selectively radiating a wave of nominally constant carrier frequency in the direction of the obstacle, a directional superheterodyne receiver receiving radiation reflected from the obstacle including a frequency converter, a source of frequency equal to the intermediate frequency of said superheterodyne receiver, a modulator connected to receive as joint inputs potentials at the frequencies of said high frequency and intermediate frequency sources, respectively, a band-pass filter for selecting from the output of said modulator one of the side frequencies, and circuit means for supplying the output of said filter to said converter jointly with the received signal at the frequency of said transmitter for reproducing the said intermediate frequency.
15. A target locating system comprising a transmitter having a transmitting oscillator and a directional radiator connected thereto for radiating a carrier wave of nominally constant frequency but subject to frequency drift, said radiator being adjustable for selectively radiating in the direction of the target, a directional receiver for receiving radiation reflected from the target, said receiver being of the superheterodyne type and including a frequency converter for reducing the received signal to an intermediate frequency, means for supplying a heterodyning frequency to said converter including a source of modulating frequency harmonically related to said intermediate frequency, a modulator receiving as inputs a substantially constant carrier frequency potential from said transmitting oscillator and a potential derived from said source of modulation, filter means for selecting one of the side frequency from the output of said modulator and circuit means connecting said filter and converter, a relatively narrow band intermediate frequency filter, means for demodulating the signal passed by said filter, and indicating means responsive to the output of said demodulator.
16. A position detecting system as claimed in claim 15 in which said modulator is a balanced modulator connected for suppressing the frequency of said oscillator.
